UNITED STATES PATENT OFFICE.

JULIAN H. RIVERS, OF ST. LOUIS, MISSOURI, ASSIGNOR, BY MESNE ASSIGNMENTS, TO UNIVERSAL FIBRE COMPANY, OF NEW YORK, N. Y., A CORPORATION OF DELAWARE.

MACHINE FOR MOLDING LIQUID-BORNE PARTICLES.

1,138,891.

Specification of Letters Patent.

Patented May 11, 1915.

Application filed December 22, 1906, Serial No. 349,146. Renewed April 1, 1912. Serial No. 687,778.

To all whom it may concern:

Be it known that I, JULIAN H. RIVERS, a citizen of the United States, residing at St. Louis, Missouri, have invented a new and useful Machine for Molding Liquid-Borne Particles, of which the following is a specification.

This invention relates to machines for molding, shaping or casting liquid borne fibrous and other particles into integral commercially usable articles; and it has for its object to produce an improved machine of the character referred to comprising a container or vessel arranged to receive a quantity of liquid suspended materials and a reticulated former or mold disposed in juxtaposition to an opening in the container to stop the suspended substances while the liquid is forced through such retained substances and through the walls of the former or mold under pressure sufficient to compact said substances into an integral object which may be used for the usual purposes of objects or articles of its class made or constructed of other material.

Another object is to produce a mold or former adapted for use in connection with a machine of the character named, having a wall or walls composed of a plurality of perforated or reticulated sections, in combination with controlling mechanism for holding said sections in rigid relation to each other while the article is being formed, and operable to withdraw said sections from contact with such article after complete formation thereof.

Particularly and specifically this invention relates to mechanism used in carrying out the process described in my Patent #804,432, issued November 14, 1905, for process of compacting liquid-borne fibrous pulp, and the process disclosed in my application for Patent Serial No. 276,179, filed August 25, 1903, for process of compacting particles; and the specific object of the invention is to produce a machine whereby commercially usable articles may be manufactured from finely divided particles by the processes disclosed in said patent and application.

In the use and operation of this machine I commence at that point where the desired amounts and proportions of the materials

to be compacted are already aggregated, so that by stirring or agitating the liquid containing them they may be thoroughly diffused as required for the best final results. I will explain the various stages and results in connection with the operation of an approved form of machine for shaping articles of one class, stating, however, that the machine can be used with equal satisfaction in producing various other articles, all of which will be readily understood by those skilled in this art.

In the drawings Figure 1 is a vertical sectional view of a machine having a mold for producing boxes. Fig. 2 is a side elevation thereof, with part of the framework broken away in order better to show some of the essential parts. Fig. 3 is a view of the under side of the bottom of the container and former. Fig. 4 is a section thereof, and Fig. 5 shows the construction of the supporting wall of the former.

The structural features of the machine illustrated which are involved in the practice of the invention, comprise a tank or container 1 having an inlet 2 through which the materials to be compacted, and the liquid or a portion thereof may be fed. The inlet should be provided with means for closing, such, for instance, as the float valve 3, which will be forced to closed position whenever the tank or container becomes filled. The bottom 4 of the container is concave or depressed and has an opening 5 through which the contents may pass to the former or formers, supported underneath. The former shown consists of the perforated metallic sheets 6 attached to hinged supports 7. Across the inner faces of said supports are formed V-shaped grooves 8 and intersecting the same on the outer faces of said supports similar grooves 9 are formed, said grooves being of sufficient depth to cut into or intersect the grooves 8 and form holes 10. The supports 6 are attached to the plates 11 which are hinged at 12 so that they may be swung outward at times. Toggle connection 13 may be utilized to control and brace the sides in operative position, and in rigid relation when in mold form.

A vertically movable bottom is supported below the sides 6. This bottom is of the

same construction as the sides, consisting of a perforated plate or screen 14 and a grooved and perforated support 15. The latter is attached to supporting members 16 operating through guides 17 and connected at their lower ends to a shaft 18 which is upheld by links 19 carried by a shaft 20 on the lower ends of the links 21, suspended by the frame of the machine. The ends of the 10 shaft 18 operate in guides 22. By swinging the shaft 20 outward as indicated by dotted lines in Fig. 1, the bottom will be lowered a sufficient distance to permit removal of the article compacted in the formers.

15 The water outlets through the bottom and walls of the former or mold become larger and larger as the distance from the inner surface increases. Water ejected through holes in thick material which do not increase in size toward the exit ends adheres in more or less quantity within the holes. Absorbent material placed against the surface of the material having the holes will draw back the moisture adhering within 20 such holes. The objects formed from fibrous material by this machine are usually absorbent until subjected to subsequent chemical treatment and would draw back and reabsorb any water adhering in the outlets. To minimize this re-absorption the water outlets are of increasing size from the inner or mold surface outward, so that the drops of water do not encounter all sides of the outlets and, therefore, do not meet 25 with the air resistance nor resistance of adhesive attraction which is met by water leaving small holes which do not enlarge in the direction of flow.

30 23 indicates a valve controlled inlet 40 through which additional liquid may be injected into the container. This inlet enters, preferably, near the bottom, and is injected obliquely upward (Fig. 1), so that liquid entering therethrough will agitate and assist 45 in diffusing the contents of the container.

In practice the fibrous and other material or materials to be molded or formed, mixed with more or less liquid, are put into the container through the inlet 2, and at 50 the same time liquid is injected into the container through the inlet 23, the flow thereof continuing until the container is nearly full, or until the valve 3 is closed.

55 The stream of liquid so injected agitates the contents and causes the materials that are to be compacted to become thoroughly diffused. As soon as the materials are put into the container the liquid commences to flow through the perforated sides and bottom of the former with nearly equal speed. This movement and escape of the liquid results in the deposit of some of the fibrous material against the sides and bottom of the former or mold, the perforations there- 60 65 in being too small to permit passage of

said material. The fibers being thus laid across the holes stop the material following, as the liquid flows, or is forced, through the former. After the container has been filled, and after a portion of the material 70 has been deposited against the walls and bottom of the perforated former, compressed air or steam is admitted into the container, preferably above the contents, through an inlet pipe or conduit 24. The 75 inrushing air, because of its natural tendency to expand, quickly and forcefully drives all the liquid through the perforated former, and the liquid carries the fibrous and other material into the said former and 80 evenly compacts and felts the same therein, the walls and bottom of the former shaping the exterior of the product. If light substances alone are to be compacted, the water or liquid entering through the pipe 23 will 85 cause approximately even diffusion of such substances. If heavy substances are included, the liquid nearer the top of the container will be somewhat clearer than that at the bottom. Heavy and light particles, 90 such as fibrous pulp and powdered cements or other minerals may be mixed together to form a composite article, in which case the pulp will be nearly evenly distributed in the liquid while the mineral substances 95 will be heaviest near the bottom. In such case the cement in the finished product will be densest near the surface first formed while the greatest quantity of pulp will be toward the surface last formed, but there 100 will be no stratification or formation of layers. This is the structure of highest efficiency for many articles such as boxes which are subject to frequent handling and the exterior of such articles should be the 105 first formed. The pressure is continuous until all of the water is driven out through, and all of the other material into, the perforated former or mold. Then the pressure is cut off and the product removed from the former by lowering the bottom upon which the product rests, the sides at the same time swing outward on their hinged supports in order to give free movement. The product may then be removed manually from the bottom and the latter returned to closed position when the machine 110 is ready for further use.

115 While I have shown a machine having a capacity of shaping or forming one article 120 at a time, it is obvious that machines may be used which have a plurality of formers, and that many articles may be produced at each operation. After removal, the articles may be subjected to heat or chemical treatment, though this may be found inessential in many instances. The mechanism may be varied within equivalent limits without change of result or of quality of the 125 product, and without in the least depart- 130

ing from the spirit and scope of the invention, and.

Hence without restricting myself to exact features, what I claim as new and desire to secure by Letters Patent is:

- 5 1. In a molding machine, the combination with a series of pivoted wall sections, and a perforated plate supported on the inner side of each of said sections, of a bottom section 10 operable effectively to move said wall sections together effectively to position said plates in the form of an inclosure, and a container opening into the inclosure formed by said wall sections and said bottom, substantially as specified.
- 15 2. The combination with a container, of a mold composed of a series of sections pivoted to said container, a bottom section, links supported by said container, and connections between said links and said bottom section whereby operation of said links will move said bottom section, substantially as specified.

- 20 3. The combination with a container, and a mold, of links pivotally supported by said container, a shaft supported by said links, other links supported by said shaft, a member carried by said second named links, and a connection from said member to said 30 mold whereby operation of said links will open and close said mold, substantially as specified.

- 25 4. The combination with a container, and means for introducing material to be molded into the container, of a series of mold sections pivoted to the container, a bottom section supporting said pivoted sections, and means for holding said bottom section against said pivoted sections, substantially 40 as specified.

- 35 5. The combination with a container, of a mold composed of a series of sections pivoted to said container, and a bottom section arranged to hold said pivoted sections 45 together, substantially as specified.

- 40 6. The combination with a container, of a mold composed of a series of sections pivoted to said container, a bottom section, and means for operating said bottom section into and out of engagement with said pivoted sections, substantially as specified.

- 45 7. A mold comprising a support, a series of wall forming sections pivoted to said support, and movable into and out of contact with each other effectively to constitute and to open the walls of the mold, and a bottom section operable effectively to move said wall sections into engagement with each other, substantially as specified.

- 50 8. A mold comprising a support, a series of perforated wall sections pivoted to said support, a bottom section holding said wall sections together, and levers operable to release said bottom and wall sections, substantially as specified.

9. A mold comprising a support, a series of wall sections pivoted to said support, a perforated plate carried by each of said sections, devices operable to move said sections into and out of contact with each other effectively to constitute and to open the walls of the mold, and a bottom section supported by said "devices," substantially as specified.

10. A mold comprising a support, a series of wall forming sections pivoted to said support, a bottom section, a shaft supporting said bottom section, guideways in which said shaft is movable, and manually operable connections to move said shaft and thereby close the mold, substantially as specified.

11. A mold comprising a support, a series of wall sections pivoted to said support, a bottom section, and manually operable connections for moving said bottom section effectively to lock said wall sections in engagement with each other, substantially as specified.

12. A mold comprising a support, a series of wall sections pivoted to said support, a bottom section holding said wall sections in engagement with each other, and pivoted connections for releasing said bottom section and thereby the wall sections, substantially as specified.

13. In a machine of the character described, the combination with the container, of a series of mold sections pivoted to said container, a bottom section, means for operating said bottom section into and out of engagement with said mold sections, and guides for said operating means, substantially as specified.

14. A machine for molding particles, comprising an agitation container, mold wall sections pivoted to said container, a mold bottom section, and links operable to cause said bottom section to lock said wall sections in the form of the mold, substantially as specified.

15. In a machine of the character described, a container, mold wall sections pivoted to said container, a mold bottom section, links operable to cause said bottom section to lock said wall sections in the form of a mold, and means to prevent displacement of said bottom section during operation, substantially as specified.

16. In a molding machine, a walled inclosure arranged to receive the materials to be molded, a bottom secured to said inclosure, a passage through said bottom, a mold supported outside of said inclosure below said bottom in position to receive the materials passing through said passage, manipulative means supporting said mold adjacent to said bottom, an inlet passage whereby materials may be delivered into said inclosure, means for closing said inlet passage, and a passage

opening upwardly into said inclosure in a direction away from said bottom, substantially as described.

17. A machine for molding plastics and other materials, comprising a container arranged to receive the materials to be molded, a bottom for said container, a passage for delivering materials into said container, a passage opening into said container near 10 and in a direction away from said bottom, a valve controlling said last named passage, a passage for admitting pressure into said container, a mold supported below said bottom, a passage through said bottom for delivering materials from said container into said mold, and a support operable to move said mold toward said bottom in position to receive the materials from said last-named passage, substantially as described.

18. In a molding machine, a container arranged to receive the materials to be molded, a perforated mold at the bottom of said container, a passage whereby materials to be molded may be delivered into said container, 25 means for closing said passage, a valve-controlled passage for admitting pressure into said container, a passage for admitting fluid upwardly into said container above said mold, and means supported by said container for moving said mold away from said container, substantially as specified.

19. In a machine for molding fibrous and other materials, a container arranged to receive the materials to be molded, a passage 35 whereby the materials may be delivered into said container, means for closing said passage, a mold at the bottom and outside of said container, links supporting said mold, a passage for admitting fluid in an upward direction into said container above said mold, a valve controlling said passage, and lever mechanism for mechanically moving said mold away from said container to enable the molded objects to be removed from 40 said mold, substantially as specified.

20. In a machine for molding plastics, a container arranged to receive the materials to be molded, a passage whereby the materials may be delivered into said container, 50 a reticulated closure at the bottom of said container, a series of links supporting said closure, a passage for delivering liquid into said container in an upward direction above said reticulated closure, a valve controlling said last-named passage, a valve-controlled passage for admitting pressure into said container, a support for said reticulated closure and lever mechanism for operating said support effectively to move said reticulated closure away from said container to enable objects to be removed from said closure, substantially as specified.

21. A molding machine comprising a container arranged to receive the materials to be molded, a reticulated former at one side

of said container, a swinging frame supporting said former, separate passage for admitting pressure and fluids into said container and lever mechanism for moving said reticulated former into and out of engagement with said container, substantially as specified.

22. In a molding machine, a container arranged to receive the materials to be molded, a passage for delivering the materials into 75 said container, means for closing said passage, a passage opening into said container near its top, a passage leading upwardly into said container near the bottom of said container, a mold supported outside of said 80 container, a frame on which said mold is mounted, a series of links supporting said frame and a passage leading from said container into said mold, substantially as specified.

23. In a machine for molding plastics, a container arranged to receive the materials to be molded, a mold supported outside of said container, a frame supporting said mold, links supported by the top of said 90 container, and supporting said frame, a passage from said container into said mold, latching devices for holding said mold in closed adjustment, and lever connections whereby said links will move said mold to 95 position to receive materials from said passage from said container, substantially as specified.

24. A machine of the character described, comprising a container arranged to receive the materials to be molded, separate passage for admitting pressure and fluids into said container, a reticulated mold supported outside of said container, a swinging frame on which said mold is mounted, a device for moving said frame and mold away from said container, and a passage from said container into said mold, substantially as specified.

25. A machine of the character described comprising a container arranged to receive the materials to be molded, links supported by said container, a mold, a vertically movable frame on which said mold is mounted, a passage from said container into said mold, 110 connections whereby operation of said links will move said frame and mold toward and away from said container, and means for admitting pressure into said container, substantially as specified.

26. A machine of the character described, comprising a container arranged to receive the materials to be molded, a mold movably supported outside of said container, a vertically movable frame supporting said mold, 115 guides in which said frame is movable, a passage from said container into said mold, means for moving said frame vertically in said guides to move said mold into and out of position to receive materials from said 120

130

passage, and a passage opening upwardly into said container above said mold and above said first-named passage, substantially as specified.

5. 27. A machine of the character described, comprising a container arranged to receive the materials to be molded, a bottom for said container, a passage for admitting pressure into said container near the top thereof, a passage opening into said container near and in a direction and away from said bottom, a mold below said bottom, a passage through said bottom for delivering materials into said mold, and mechanism 10 for supporting said mold in closed position to receive the materials from said last-named passage and in open position to enable the articles to be removed after they have been molded, substantially as described.
20. 28. In a machine of the character described, a container arranged to receive the materials to be molded, a bottom for said container, a discharge passage for the materials through said bottom, a mold supported independently of said bottom, a manipulative support for holding said mold in closed position to receive the materials through said passage and operative to enable said mold to move with respect to said bottom, a passage opening into said container adjacent and in the direction away from said bottom, and means for admitting pressure into said container near the top thereof, to force the materials out of said container into said mold, substantially as described.
30. 29. In a machine of the character described, a container arranged to receive the materials to be molded, a bottom secured to said container, a passage opening into said mold adjacent and in a direction away from said bottom, a passage for admitting pres-

sure into said container near the top thereof, a mold outside of said container, a support movable to support said mold in closed position adjacent to said bottom or in open position away from said bottom at the will of the operator, and a passage through said bottom opening into said mold, substantially as described.

30. 27. A machine of the character described, a container arranged to receive materials to be molded, a bottom for said container, a passage through said bottom, a mold outside of said container, means for supporting said mold in closed position to receive the materials through said passage or in open position to enable the articles to be removed, as desired, and a passage for admitting pressure into said container near the top thereof to force the materials into said mold, substantially as described.

31. In a machine of the character described, a container arranged to receive the materials to be molded, a bottom for said container, a passage for said container, a passage through said bottom, a mold outside of said container and below said bottom, manipulative means for supporting said mold in closed position to receive the materials discharged through said passage and in open position to enable the articles to be removed, and a passage opening into said mold adjacent to and in a direction away from said bottom and the said passage therethrough, substantially as described.

In testimony whereof, I hereunto affix my signature to this specification this 23d day of October, 1906, in the presence of two witnesses.
